[57] CLAIM

The ornamental design for a freezer alarm, as shown and described.

DESCRIPTION

FIG. 1 is an isometric view of a freezer alarm showing my new design;

FIG. 2 is a top plan view thereof;

FIG. 3 is an end view thereof, taken generally from a position toward the right side of the illustration of FIG. 1;

FIG. 4 is a bottom plan view of my freezer alarm;

FIG. 5 is an end view similar to FIG. 3, but taken from a position generally to the left of the illustration of FIG. 1;

FIG. 6 is a front elevational view of my freezer alarm; and,

FIG. 7 is a rear elevational view thereof.

FIG. 1

FIG. 2
